UNITED STATES PATENT OFFICE

JOHN BLENKER, OF NEENAH, WISCONSIN

DESIGN FOR A COMBINATION SERVICE TRAY AND PLATE

Application filed February 15, 1932. Serial No. 42,877. Term of patent 14 years.

To all whom it may concern:

Be it known that I, JOHN BLENKER, a citizen of the United States, residing in the city of Neenah, in the county of Winnebago and State of Wisconsin, have invented a new, original, and ornamental Design for a Combination Service Tray and Plate, of which the following is a specification, reference being had to the accompanying drawing, forming a part thereof, in which Figure 1 is a plan view of the combination service tray and plate showing my new design.

I claim:

The ornamental design for a combination service tray and plate as shown.

In testimony whereof I affix my signature.

JOHN BLENKER.
